UNITED STATES PATENT OFFICE.

RANDOLPH H. GIBSON, OF CHICAGO, ILLINOIS.

DESIGN FOR A CIGAR-LIGHTER CABINET.

Application filed June 2, 1927. Serial No. 22,283. Term of patent 3½ years.

To all whom it may concern:

Be it known that I, RANDOLPH H. GIBSON, a citizen of the United States, residing at Chicago, in the county of Cook and State of Illinois, have invented a new, original, and ornamental Design for Cigar Lighter Cabinets, of which the following is a specification, reference being had to the accompanying drawings, forming part thereof.

I claim:

The ornamental design for a cigar lighter cabinet, as shown.

RANDOLPH H. GIBSON.
